UNITED STATES PATENT OFFICE.

WILLIAM J. WRIGHT, OF PITTSBURG, PENNSYLVANIA, ASSIGNOR OF SEVEN-SIXTEENTHS TO JOHN F. MCKIBBEN, J. W. LEE, AND FRED J. GALLOWAY, OF PITTSBURG, PENNSYLVANIA.

GAS-ENGINE.

SPECIFICATION forming part of Letters Patent No. 732,683, dated June 30, 1903.

Application filed July 20, 1900. Serial No. 24,324. (No model.)

To all whom it may concern:

Be it known that I, WILLIAM J. WRIGHT, residing at Pittsburg, in the county of Allegheny and State of Pennsylvania, have invented a new and Improved Gas-Engine, of which the following is a specification.

This invention is in the nature of an improved explosive-engine wherein the gaseous pressure in a cylinder resulting from the combustion of a mixture of air and an inflammable gas or vapor is caused to operate a piston coupled to a crank-shaft.

My invention seeks to provide certain improvements in this type of engines whereby to produce very compact, economical, and effective operating mechanism of the character stated and by which an explosive impulse can be transmitted to the crank-shaft at each quarter of its revolution.

In its more generic features my present invention comprehends two working cylinders in each of which is a working piston, the two pistons being set to operate alternately and each piston shifted in its opposite directions by an explosive force taking place alternately at opposite ends thereof, each piston being sent forward by an explosive charge twice during a complete revolution of the shaft, and by reason of the alternate setting of the pistons the shaft thereby receives an impulse at each quarter of its movement.

This invention also has for its purpose to provide an explosive-engine having but few parts compactly arranged, in which cams, eccentrics, and like devices commonly used for shifting the valves are dispensed with and in which a maximum amount of power is obtainable with a minimum arrangement of structural parts and consumption of fuel.

My present invention also embodies a novel correlation of a pair of working cylinders, each working in harmony with a special arrangement of pumping or cross-head cylinder and in which but a single piston-rod is used for each set of working and pumping cylinders, having a pair of piston-heads, one for the working cylinder and one for the pumping cylinder, the latter serving as a cross-head and maintaining the working piston in such proper position within the working cylinder

that danger of said working piston and the cylinder wearing off irregular, as is commonly done in engines having the pistons centrally joined to an oscillating piston-rod, is avoided.

Another and essential feature of my present invention lies in the novel correlation of two distinct sets of operating devices for controlling and exploding a working charge and novel means for joining the two sets of operating devices with a single working-agent feed, 55 said novel means including a single valve mechanism arranged to operate at predetermined intervals to feed to one set of operating devices and then to the other set in such manner as to provide for creating a working 60 charge and exploding at one end of the piston in one working cylinder, then at the same end of the piston in the other working cylinder, then at the opposite end of the first piston, and then at the same end of the second piston, 65 the said invention in its complete make-up also including an automatically-operating cut-off and feed mechanism for exhausting the working cylinders first under the expansion of the force of the exploded charge and 70 then under pressure of a new charge of pure mixture being supplied against the remaining burned charge.

In its more subordinate nature my present invention consists in certain novel features 80 of construction and combination of parts, all of which will hereinafter be fully described, and particularly pointed out in the appended claims, reference being had to the accompanying drawings, in which—

Figure 1 is a top view of my improved engine, the working and the pump cylinders at one side being shown in horizontal section. Fig. 2 is a horizontal section of the governor-valve for regulating the feed of the working 90 agent to the pumping-cylinders, taken on the line 2 of Fig. 4. Fig. 3 is an inverted plan of the rotary valve member forming a part of the device shown in Figs. 2 and 4. Fig. 4 is a vertical section taken practically on the line 4 4 on Fig. 2. Fig. 5 is a plan view of the mechanism governing the exhaust of the burned mixture from the working cylinders and the feed of the working charge thereto, the connecting-channels of the upper or ro- 100

tary valve member being shown in dotted lines, the said valve member not being shown. Fig. 6 is an inverted view of the rotary valve member forming part of the aforesaid mechanism. Fig. 7 is a section on the line 7 7, and Fig. 8 is a similar view on the line 8 8, taken on Fig. 5.

Referring now to the accompanying drawings, in which like characters indicate like parts in all the figures, A B designate, respectively, the working cylinder and the pumping-cylinder, forming one set of working-agent controlling and exploding mechanisms, and C D represent the working and pumping cylinders of the other set of controlling and exploding means. The pumping-cylinders B D are of like size, as are the cylinders A and C. The several cylinders are of such length as to allow for a proper predetermined stroke of the piston-heads working in them, the cylinders A and C having the usual cooling-jackets, arranged as shown in Fig. 1. All of the cylinders are mounted in the same horizontal plane in two pairs of sets, one set consisting of the cylinders D and C, mounted in the same longitudinal alinement, and the other, B and A, mounted likewise in the same longitudinal alinement parallel to the first set, the purpose of which will be hereinafter fully explained.

1 designates a piston-rod which extends into the adjacent ends of the cylinders B and A, one end of which is joined with the pump cross-head piston 2, the other end being secured to the working piston 3, it being understood that the piston-rod 4 of the other set of operating devices is similarly connected with the pistons 2^d 3^c.

40 By arranging the several working and pumping cylinders and the piston-rods 1 and 4 as described and shown, the pistons 2 2^d will serve as cross-heads for keeping the pistons 3 3^c in proper alinement and from having a rocking action within the cylinder, such as is incident in the use of the ordinary type of piston-head centrally connected with an oscillating pitman or crank rod.

As a further means for holding the two pistons 2 2^d and 3 3^c in proper alinement, and particularly for providing a compact and economical engine structure and to dispense with the ordinary type of cross-heads, I connect each of the pistons 2 2^d directly with the 55 crank-shaft members 5^a 5^a by pitman-rods 6, whose inner ends are pivotally joined to the pistons 2 2^d, as illustrated in Fig. 1, said rods 6 oscillating in vertically-elongated slots in the heads B' D', which are normally held 60 fluid-tight by the sliding plates 7 and oscillating stuffing-box 8, (illustrated in horizontal section in Fig. 1,) and the said cranks being set one-fourth ($\frac{1}{4}$) in advance of the other. While I prefer to connect the pistons 2 2^d directly to 65 the crank-shaft, it is obvious they may each be joined to a cross-head, as is ordinarily done.

At each end of the cylinders B and D is a feed-port, said ports being designated by b b^x and d d^x in Fig. 1, and the several ports communicate with pipe-sections 9, 9^a, 9^b, and 9^c, that connect with a single governor-valve mechanism, the detailed construction of which is illustrated in Figs. 2, 3, and 4, by reference to which it will be seen the same 75 consists of a stationary base 10, mounted upon a suitable support a. The base 10 has an annular feed-channel 11, (through which flows the mixed air and gas working agent,) with which communicate four inlet-ports b', a', d', and c', said ports extending to the top of the base 10, as clearly seen in Fig. 2. The ports b', a', d', and c' are arranged on quarters, and adjacent said ports are escape-ports b², a², d², and c², that discharge into the pipes 9, 9^a, 9^b, 85 and 9^c, respectively.

12 designates the rotary valve member, held to rotate upon the base 10, upon which it is secured to run freely and uniformly by the flange-ring 13, made fast to the base 10 and 90 having an inwardly-extending flange 13^a. (See Fig. 4.)

Upon the under side the valve member 12 has a pair of concentrically-arranged feed-channels 14 and 15 in the same radial alinement and extending nearly one-half around the valve-seat, the outer channel 14 being nearest the perimeter, whereby to travel over the several sets of ports a' a² and d' d², and the inner channel 15 travels over the ports b' 100 b² and c' c², said channels being so arranged as to open up communication at proper predetermined times alternately with the pump-cylinders B D.

So far as described the manner in which my 105 improved engine operates, particularly as to the feeding of the working agent to the two cylinders B and D, is best explained as follows: The valve 12 is mounted upon the squared end 16^a of a shaft 16, held to rotate 110 in the base 10, and the lower end of which carries a miter-gear 17, that meshes with a similar gear 18 on the drive-shaft 19, geared with the crank-shaft, as shown in Fig. 1, the gear connections between the shafts being such 115 that the valve 12 will make a complete revolution at each complete turn of the crank-shaft, whereby the ports for the cylinder B will be first properly adjusted, then the ports for cylinder D, and so on successively. Assuming now the pistons 2 and 3 as moving in the direction of the arrow Y in Fig. 1 and the piston 2 just reaching the limit of its movement in the direction indicated, the charge in front of it now having gone out to the explosion-cylinder in a manner presently fully explained the channel 15 in the valve 12 will just be bringing the port b², that discharges into pipe-section 9, into communication with the feed-port b', and the working agent will 125 then begin to flow through the inlet b at the left-hand end of the cylinder B in Fig. 1. At the same time the cylinder D will be taking a flow of working agent back of the piston 2^d

through the feed-inlet d^x under a full head, the piston 2^d being at this time at the center of its stroke, the prior charge in front of the piston flowing to that end of the working cylinder in communication therewith. Thus by arranging the channels 14 and 15 in the valve 12 and the several ports as described as soon as the piston 2^d reaches that point of the finish of its stroke at the left-hand end 10 of the cylinder D—that is, at a point where the charge in front of it escapes—the feed-supply through the ports $d^1 d^2$ will be cut off, while the supply through the inlet b at the left of piston 2 will now be under a full head, the piston 2 being at this time at the center of its stroke in the direction of arrow Y'. When this occurs, the outer channel 14 (going in the direction of arrow Z in Fig. 2) will just be beginning to open up the inlet a' to 15 outlet a^2 to permit the working agent to flow into pipe 9^a , that discharges through inlet d at the left-hand end of cylinder D, it being manifest that the continued movement of the valve 12 will bring the ports $c' c^2$ into communication to open up the flow through pipe 9^c to the inlet b^x of the cylinder E. Thus a 20 single regulating mechanism including a continually-rotating valve regulates the inflow of the working agent to the opposite ends of 25 the pumping-cylinders in such manner that an explosive mixture is drawn in at each quarter-turn of the crank-shaft.

For regulating the exhaust and supply ports of the two working cylinders a governor or 30 regulating mechanism similar in construction and action to the governor devices for the pump-cylinders is employed, said mechanism having in addition to the several sets of inlet-ports coacting exhaust-governing 35 outlets, the arrangement of which is clearly 40 shown in Figs. 5 and 6.

The working-cylinder-controlling devices (indicated generally by XX) consist of a base portion 20, having a series of quadrally-arranged ports disposed in pairs and indicated by $d^3 d^4$, $b^3 b^4$, $a^3 a^4$, and $c^3 c^4$. The port d^3 45 communicates with a pipe b^6 , that connects with a discharge-outlet d^5 in one end of cylinder D. The port b^3 communicates through 50 pipe d^6 with the discharge-outlet b^5 in cylinder B. The port a^3 connects through pipe a^6 , with the outlet d^7 in cylinder D, and the port c^3 communicates through pipe b^8 with the outlet b^7 of cylinder B.

55 The outlets d^4 , b^4 , a^4 , and c^4 discharge, respectively, into the feed-openings a^{10} , c^{10} , b^{10} , and d^{10} of the working cylinders.

25 designates the rotary valve of the governor devices XX, the seat of which is also 60 provided with two concentric feed-channels 25^a 25^b , which are, however, of much less length than the like channels in valve 12 of the pump-feed-governor devices, to effect a quick action in leading the charge from the pump-cylinders into the opposite ends of the working cylinders, the two channels 25^a 25^b being 65 also of such relative arrangement that while

the outer one, 25^a , is in position to allow a wide-open feed through ports $d^3 d^4$ through the port a^{10} in cylinder A the other channel, 70 25^a , will just be beginning to open up a charge through port b^4 to port c^{10} in cylinder C, it being manifest that when the valve 25 is rotated an additional half-revolution the same relative adjustments for ports a^4 and c^4 for 75 leading the charge to the ports b^{10} and d^{10} of the working cylinders is effected.

The governor devices XX are also arranged to provide for exhausting the burned mixtures from the cylinders A and C, and for such purpose said devices include a series of ports arranged in pairs, one set, $d^{30} d^{40}$, being adjacent the ports $d^3 d^4$, a second set, $b^{30} b^{40}$, registering with the ports $b^3 b^4$, a third set, $a^{30} a^{40}$, being adjacent the ports $a^3 a^4$, and a fourth set, $c^{30} c^{40}$, adjacent the ports $c^3 c^4$.

The ports d^{30} , b^{30} , a^{30} , and c^{30} each communicate with an offtake-pipe, indicated, respectively, by 30^a , 30^b , 30^c , and 30^d , that communicate with the exhaust-ports of the two 90 working cylinders, as clearly shown in Fig. 1, while all of the ports d^{40} , b^{40} , a^{40} , and c^{40} empty into an exhaust-channel 50, which discharges into atmosphere, as indicated at 95 50^a in Fig. 5.

The valve 25 is made of sufficient diameter to extend over the several exhausts during its cycle of rotation, and it has a supplemental pair of feed-channels 55 56, in practice so disposed that when the one, 55, is full over any 100 one pair of the two sets of exhaust-ports with which it is co-operatively arranged the other channel 56 will be in a position just beginning to connect the next pair of exhaust-ports forward, as indicated in dotted lines in Fig. 105 5, by reference to which it will also be noticed the channels 55 56 are of greater length than the channels 25^a and 25^b and are so placed on the valve 25 as to come into an operative condition in advance of the channels 25^a 25^b , so 110 as to bring the ports (say $d^{30} d^{40}$) into position to exhaust before the feed-ports (say $d^3 d^4$) are connected to allow for a charge of the working agent entering the end of the working cylinder fed from the port d^4 , the length 115 of the channels 55 56 being such, however, that the exhaust-ports (say $d^{30} d^{40}$) will still be in open communication with each other and atmosphere after the feed-ports (say $d^3 d^4$) are opened up for the passing of the working 120 charge therethrough, the reason for which will be presently explained.

The operation of my engine is as follows: Assuming the last explosion as having taken place in that end of cylinder A indicated by 125 A⁵ and the piston-heads 3 2 traveling in the direction indicated by arrow Y under explosive impulse, at this time the valve 12 in the feed-governor devices will move into position to gradually open up a feed of working 130 charge through the inlet b^x back of the piston-head 2, which comes to a full head when the piston reaches the center of its stroke, (indicated by line O.) It should be stated

the feed and exhaust governing devices XX have the valve 25 then so timed that when the piston 3 passes the center (indicated by line O O) and when the force of the expansion or explosive force of the last-ignited charge has spent itself the exhaust-ports d^{30} d^{40} will be brought into communication, and thereby allow the bulk of the burned mixture to blow out to atmosphere and begin to leave end A⁵ of cylinder in condition for a fresh charge, which immediately after the bulk of the burned mixture passes out enters from pipe b⁶ and the ports d^3 d^4 , the feed-governor valve 12 being so placed to allow the new charge in front of piston 2^d being blown out into the pipe d⁶ at the proper time. The pistons 3 3^a being set to operate on quarters and an explosion being provided for at each end of the pistons during one-half revolution of the shaft, the devices for governing the feed to the pump-cylinder and the feed of the working agent and the exhausts from the working cylinders are so arranged relatively and have their respective valves so coöperatively connected with a drive-power geared with the crank-shaft that when the piston 2 reaches the center O the working agent will begin to enter through inlet d in cylinder D.

Among other advantages my form of engine can be very economically constructed, and by reason of the manner in which the working agent is fed into the cylinders A and D and the manner in which the burned mixture is exhausted the said engine becomes one of great capacity with a very little consumption of fuel.

One of the essential features of my invention is that a single valve mechanism is provided for the working-agent feed, which when once set will at all times maintain its proper operative condition, thus dispensing with the use of cams, trips, and eccentrics so common in the ordinary type of the explosive-engines. Again, in my construction of engine the feed-ports have no valves or cut-off devices governed by the explosive force of the engine, all of the feed-ports being governed by a valve device having a uniform action geared directly with the crank-shaft.

Another and important feature of my invention is that the explosion-chamber of the cylinders D and A are materially exhausted of the burned mixture before the new charge enters, thereby providing for a pure mixture being fed to the cylinders D and A, it being understood that whatever residuum remaining in the explosion-chamber when the new charge enters will be blown out by the new charge.

Any well-known means for igniting the charges in the cylinders D and A may be provided—as, for example, electric means energized at the end of the stroke of the pistons 3 3^a.

Another and very important advantage of my construction of engine is that no power is lost by compressing the working-agent charge

twice, as is common in the ordinary types of two-cycle engines, for the reason that the mixture in advance of the pump-piston is forced into the working cylinder by the forward movement thereof as the working piston passes over its center.

Having thus described my invention, what I claim, and desire to secure by Letters Pat- ent, is—

1. In a gas-engine, the combination of two pumping-cylinders B D, two working pistons 3 3^a, the cylinders A and C therefor, the crank-shaft, and an automatically-operating means governed by the crank-shaft adapted to feed the working agent into the two pumping-cylinders successively, first into one end of pump-cylinder B, then into same end of the other pump-cylinder D, then exhausting the charge in front of the piston in cylinder B, and then feeding a charge into other side of the piston in cylinder B, as set forth.

2. In an engine of the character stated; the combination with two sets of cylinders, a piston in each cylinder, the shaft having suitably-arranged cranks with which the two pistons connect, and a working feed; of a single governor mechanism including a continuously-operating valve arranged to first open the explosion end of one of the working cylinders to atmosphere, then open a working-charge feed thereto as the other cylinder is taking an advance feed of the working agent in front of one end of its piston, and condensing a prior charge on the other end, ready for exploding, as set forth.

3. An improved gas-engine comprising two working cylinders, each having a feed inlet and exhaust, at each end thereof; a working-agent feed mechanism connected with the feed-ports, one set in advance of the other, and a valve mechanism governed by the rotation of the crank-shaft, said mechanism including a valve adapted to first open up the end of one of the cylinders to exhaust the burned mixture while it feeds to the corresponding end of the other cylinder and then feeds to the said explosion-chamber while still feeding to the same end of the other cylinder, as specified.

4. A gas-engine comprising a pair of working cylinders, a pair of pumping-cylinders, a piston for each set of working and pumping cylinders, said piston including a head operating in the pump-cylinder, and a head operating in the working cylinder, the two pistons operating alternately, each pump-cylinder having an induction and a discharge port at each end, the working cylinder having at each end an inlet and an exhaust port, a working-agent supply, a governor mechanism including a shifting valve for the supply, said valve controlling the predetermined opening and closing of the induction-ports in the pump-cylinder, a second shifting valve in the governor mechanism in communication with the induction-ports of the pumping-cylinders and with the inlets and exhausts of the working

cylinder, said last-named shifting valve controlling the predetermined opening and closing of the inlet and exhaust ports in the working cylinders, the two controlling-valves having gear connections with a continuously-operating part of the engine, for the purposes specified.

5. A gas-engine comprising a pair of working cylinders, a pump-cylinder for each working cylinder, arranged in the same longitudinal plane therewith, a single piston for each set of pump and working cylinders, said piston having a head operating in the working cylinder, and a head operating in the pump-cylinder, the pump-cylinder having a feed-inlet and a discharge in each end, the discharges of one pump-cylinder communicating with the inlets of the other working cylinder, a working-agent feed, means for exhausting 15 the working cylinders in advance of the new charges supplied thereto, and means for automatically controlling the feed of the charges into the two working cylinders, as set forth.

6. The combination with the working cylinders A C, each having inlets and exhausts in the opposite ends and a piston for each, operating between said inlets and exhausts; of the pump-cylinders B D, the cylinders B and D, being respectively in line with the working 25 cylinders A and C, having their piston-heads connected to and movable in unison with the pistons in the cylinders A and C, the pumping-

cylinders having each a feed-induction and a discharge port in each end, the discharge-ports of the cylinder D, being connected with the 35 inlets of the cylinder A, and those of cylinder B, with cylinder C, and valve mechanism for controlling the inflow and outflow to and from the pump-cylinders, whereby a charge in advance of the piston in the cylinders B and D, 40 will pass out to the working cylinders co-operating therewith as a new charge is drawn in back of the pump-pistons, as specified.

7. In a gas-engine as described, the combination with the two working cylinders, and a 45 pumping means for storing up a charge for one working cylinder as it forces a new charge into the other working cylinder; of a valve mechanism for controlling the inflow of the charges to the two working cylinders, said 50 valve mechanism being in communication with the pumping means, and having supplemental ports adapted at a predetermined time to set the said mechanism to open up the exhaust-ports of the working cylinder to atmosphere, and before said ports are cut off to open up the ports for the passing of a new charge into the cylinder end being exhausted, as set forth.

WM. J. WRIGHT.
